Primary Examiner — Jennifer Rivard(74) *Attorney, Agent, or Firm* — Joanne N. Pappas; Kevin C. Johnson(57) **CLAIM**

The ornamental design for a razor handle, as shown and described.

DESCRIPTION

FIG. 1 is a front perspective view of a design of a razor handle of the present invention;
FIG. 2 is a front view thereof;
FIG. 3 is a back view thereof;
FIG. 4 is a right side view thereof;
FIG. 5 is a left side view thereof;
FIG. 6 is a top view thereof;
FIG. 7 is a bottom view thereof; and,
FIG. 8 is a rear perspective view.

The razor head that is shown in evenly spaced broken lines illustrates the environment of the claim. The remaining evenly spaced broken lines illustrate portions of the razor handle. The dash-dot-dash broken lines illustrate the boundary of the claim. Neither the evenly spaced broken lines nor the dash-dot-dash broken lines forms part of the claimed design.
